METHOD OF CONSTRUCTING SLIPPERS

Benjamin Wunsch, New York, N. Y., assignor of
one-half to Isidor Wunsch, Bronx, N. Y.

Application January 8, 1947, Serial No. 720,792

2 Claims. (Cl. 12—142)

1

This invention relates to slippers and similar footwear of the type employing a soft insole and a hard outer sole with means for finishing and uniting peripheral edge portions of the soles and the corresponding edges of the uppers. Still more particularly, the invention deals with a new method of assembling and attaching the parts so as to produce a neat and finished appearance and to control, to a large degree, sizing of the slipper upper in attaching the same to a pre-sized hard sole. Further, my invention deals with footwear of the kind described and a method of producing the same wherein an intermediate or spacer sole is employed to produce a thicker sole structure and, further, to raise the heel portion of the footwear.

The novel features of the invention will be best understood from the following description, when taken together with the accompanying drawing, in which certain embodiments of the invention are disclosed and, in which, the separate parts are designated by suitable reference characters in each of the views, and in which:

Fig. 1 is a side elevation of a slipper showing one adaptation of my invention.

Fig. 2 is a sectional view through part of an upper and part of an inner sole illustrating the method of attaching the same together.

Fig. 3 is a view similar to Fig. 2 showing the method of attaching a binder or finishing strip to the joined edges of the insole and upper.

Fig. 4 is a section on the line 4—4 of Fig. 1 on an enlarged scale, showing the complete assemblage with the outer or hard sole stitched in position.

Fig. 5 is a side and sectional view of a modified form of outer sole which I employ; and

Fig. 6 is a side view of a part of a slipper employing the sole of Fig. 5 with part of the construction broken away and in section.

In Fig. 1 of the drawing, I have shown in illustrating one adaptation and use of my invention a slipper 10, comprising an upper formed from separately stitched or otherwise united parts namely a toe and side wall portion 11, a top wall portion 12 and a rear heel portion 13 having an upwardly extending flange portion 14 which may be used in the raised position shown in Fig. 1 or turned down to expose the inner fur or nap facing 15 of the skin or leather from which the sole portions of the slipper are formed. In other words, in the construction shown, the slipper is of a fur-lined or skin-lined type.

Considering now Figs. 1 and 4 of the drawing, it will be seen that, secured to the walls 11 and

2

13, in a manner later described, there is an insole 16 which also preferably has the fur or other skin facing 17, at least within the body portion of the slipper. At 18 is shown the hard outer sole of facing which may be composed of a leather, rubber or composition materials of any type or kind and this may be partially secured to the insole 16 by a suitable adhesive.

In constructing the footwear such as the slipper shown, the walls 11 and 13 of the upper are first secured together and, then, to the insole 16 by a cast-over or other stitching 19 as clearly seen in Fig. 2 of the drawing so as to reinforce and strengthen the joined edges of the relatively soft side walls and insole, the side walls having as indicated at 20 in Fig. 2 of the drawing, outwardly extending flange portions which facilitate the attachment in question.

In Fig. 3 of the drawing, I have shown the next step in the method of producing the footwear which consists in securing a finishing strip or binder 21 to the flanged edge 20 and to the outer edge portion 22 of the insole 16. The strip 21 has an inturned upper edge 23 and, in attaching 20 the strip 21, a stitching, as at 24, passes through the inturned edge 23, the flange 20, the insole 16 and the lower edge 25 of the strip 21.

The next step in the production of the slipper comprises attaching the outer hard sole 18 to 30 the insole 16. The sole 18 is preferably pre-shaped to a desired size and the sole 18 is secured in position by a line of stitching as at 26, preferably arranged outwardly of the stitching 24 and, in this operation, the upper is stretched 35 sufficiently to bring the outer flanged edge 20 of the upper and the outer edge 22 of the insole in alignment with the peripheral edge 27 of the outer sole, thus maintaining a neat and finished appearance of the resulting footwear, as well as 40 to bring the footwear to a substantially controlled size. The soft material of the upper, including the insole, is sufficient to yield to the slight strains to which the same is subjected in sizing the upper to the lower sole.

The above operation completes the formation 45 of the footwear and it will be apparent that the turned edge 23 of the binder will be arranged in the corner portion of the footwear where the side walls 11 and 13 extend upwardly, as seen at 50 28 in Figs. 3 and 4 of the drawing. As previously stated, the insole 16 may be glued or otherwise secured to the outer sole 18 and, if an adhesive is employed, this will be applied prior to the 55 stitching operation 26. However, in footwear of

the specific type and kind shown, the use of an adhesive is not absolutely essential.

In Figs. 5 and 6 of the drawing, I have shown a slight modification wherein an intermediate spacer wall 29 is employed between the insole 16' and the outer sole 18', the intermediate sole 29 being preferably thin at the toe end portion 30 thereof and considerably thicker at the heel end portion 31 so as to reach the heel. The intermediate sole 29 produces a thicker over-all sole as will be apparent.

In producing a slipper, the method shown in Figs. 2 and 3 is followed in attaching the insole 16' to the uppers 11', 13'. The intermediate sole has a facing or binder strip 32 secured to the peripheral edge thereof by a stitching, as at 33, or any other means of attachment may be provided. After the binder strip 32 has been secured in position, the outer sole 18' is first temporarily attached to the intermediate sole 29 by two or more wire staples, as at 34, or by other suitable means simply to hold these two soles in alignment with each other preparatory to stitching to the insole of the footwear. The assemblage, as seen in Fig. 5, is then secured to the footwear having the insole 16' attached thereto by a line of stitching 35 positioned outwardly of the stitching 24' for attaching the binder or finishing strip 21' to the insole 16'. After the assemblage shown in Fig. 5 has been secured to the insole 16' by the stitching 35, the temporary fastenings, as at 34, can be removed. In some types of footwear, it may be desirable to first cement the sole 18' to the intermediate sole 29 and, then, to cement the sole 29 to the insole 16' just prior to the stitching operation and so as to facilitate sizing of the upper on the outer sole unit as previously stated in connection with the structure of Figs. 1-4 inclusive.

In footwear of the type and kind disclosed, it is preferable that the upper wall 12, disposed over the toe portion of the slipper, be attached after the assemblages of the insole and outer sole, so as to give the operator full freedom and manipulation of the upper and insole in sizing the upper to the pre-sized outer or hard sole.

By constructing footwear in accordance with the method disclosed, in addition to producing a neat and finished product, the attachment between the upper and soles of the footwear is reinforced by the stitchings employed and the cast-over stitchings, such as 19, are protected by the binder or finishing strip 21. It is also preferred that the stitchings as at 26, 35 be disposed between the cast-over stitchings as, for example, at 19 and the stitchings 24, 24'. In this way, the

strain of the upper is first taken up by the stitching 24, 24' before transmission to the stitchings as at 26, 35. My improved method of forming footwear also produces a sufficiently protruding edge portion on the resulting sole to guard and protect the upper to a large degree which is particularly desirable in the construction of children's footwear.

Having fully described my invention, what I claim as new and desire to secure by Letters Patent is:

1. The method of forming footwear of the class described, which comprises first uniting side wall portions of the upper, then attaching the outwardly extending peripheral flanges at lower edges of the side walls to the corresponding edges of a soft insole, then attaching lower edges of the upper and peripheral edges of the insole to peripheral edge portions of a hard sole by a single line of stitching, and stretching the upper and insole in stitching the same together to size the upper and insole to the size determined by said hard sole.

2. The method of forming footwear of the class described which comprises first stitching peripheral edge portions of a flexible insole to outwardly extending peripheral flange portions of an upper by an overcast stitching, then securing a binder and finishing strip to said joined edge portions of the insole and upper by a line of stitching arranged at the inner portions of the flange by said upper, binding the peripheral edge of an intermediate sole, then securing said intermediate sole to the upper surface of a hard sole, and then stitching the hard sole and intermediate sole to the bound and united edges of the insole and upper by a single line of stitching.
